UNITED STATES PATENT OFFICE

FRANK C. PICKARD, OF ERIE, PENNSYLVANIA, ASSIGNOR TO THE STANDARD STOKER COMPANY, INCORPORATED, A CORPORATION OF DELAWARE

CONVEYER FOR STOKERS

Application filed December 18, 1928. Serial No. 326,869.

My invention relates to the fuel conveying system of a stoker and more especially to a novel design of conduit element commonly called an elbow. The main object of the invention is to produce an elbow which is provided with a new and improved bearing for the conveyer element or screw adapted to rotate therein.

In the stoker system for which my invention is more particularly designed, the forwardly extending portion of the conduit system leading from the source of fuel supply to the firebox of the boiler, has at its end portion an angularly disposed member or elbow which is adapted to turn or direct the fuel upward as it is conveyed or fed forward by the conveyer screw. The forward end of this screw terminates at the turn or elbow proper and as the fuel is turned or forced upward through the elbow and the riser connected thereto, the re-action tends to lift or raise the forward end portion of the screw overcoming gravity which tends to maintain the screw at the bottom of the conduit. Advantage has been taken of this fact to provide at the upper side or roof of the straight part of the elbow a reinforced portion curved to conform with the screw and providing an extended bearing surface for the outer edge or face of the screw thread as it rotates. This extended bearing, providing surface in place of point or line contact, reduces or restricts the wear and prolongs the life of the elbow.

It will be understood that when the screw is stopped, it will fall away from the bearing surface above it. The invention has the further advantage of being adapted to existing constructions without material change therein. In the example shown, the invention has been applied to an elbow having a flat roof and in such constructions it is carried out by slightly increasing the thickness or reinforcing the roof for a sufficient distance width-wise to provide for the curved bearing surface at the under side, this distance varying with the different sizes of conveyers, but in the present form shown it is some 5 to 6 inches. The thickness or reinforcing is to be ended before it reaches a point where it will interfere with the recesses provided in this

type of conduit and which have been found highly advantageous in minimizing the tendency of the fuel to rotate without being advanced or fed.

To the above and other ends which will hereinafter appear, the invention consists in the features of construction, combinations of devices and arrangements of parts subsequently set forth and particularly pointed out in the appended claims.

The invention will be described more in detail in connection with the accompanying drawing, wherein

Fig. 1 is a fragmentary elevation of the stoker embodying my invention, parts being sectioned and broken away for the sake of clearness;

Fig. 2 is a vertical sectional view taken on a plane indicated by the section line 2—2 in Fig. 1;

Fig. 3 is a perspective view of the conduit elbow or element shown detached;

Fig. 4 is a fragmentary side elevation of a modified construction; and

Fig. 5 is a vertical sectional view taken on a plane indicated by the section line 5—5 in Fig. 4.

The stoker embodying the present form of my invention is of the type employed with locomotive engines. The conduit system of the stoker comprises a conduit tube or element 10 connected at its rear to another conduit element (not shown) but which, as is well understood, is comprised in a system leading from the source of fuel supply on the tender of the locomotive. Forward of the tube 10 is an angular conduit element 11 usually termed an elbow and which is flanged at its rear end to enable it to be bolted or otherwise secured to the element 10. The elbow 11 comprises a horizontal portion 12 and an upwardly curving portion 13 which at its top is suitably connected to a riser or mouth element 14. The elbow 11 passes under the rear leg 15 of the locomotive boiler and the riser extends upward within the firebox or combustion chamber 16 of the boiler, being housed or protected by a grating 17. Means for distributing the fuel as it is forced upward out of the riser comprise a distributor

head 18 which is connected as by piping 19 with a steam or other fluid-supply system.

The elbow 11 may be formed of a single casting and may have lateral foot portions

5 11a adapted to a support 20 mounted on the framework of the locomotive indicated generally at 21.

Disposed within the conduit system is a conveyer system, the forward end portion of 10 which comprises a conveyer screw section 22 terminating at or in the vicinity of the curved portion 13 of the elbow. As is well understood, the conveyer or screw is turned or rotated by mechanical means, thus advancing 15 or feeding the fuel forward from the source of supply through the conduit system. As the fuel reaches the curved portion 13 of the elbow 11 it is turned or directed upward and forced through the riser 14 and out of its top. 20 Gravity of course tends to maintain the conveyer screw 22 down in contact with the bottom of the conduit; but the reaction at the elbow tends to lift the forward portion of the screw 22, the result being in the existing 25 devices of a cutting or wearing away of the roof portion.

Advantage has been taken of this lifting action of the screw to provide for a novel bearing in the roof or top of the horizontal 30 portion 12 of the elbow member. As will be observed from Figs. 2 and 3 said portion 12 at its under side or bottom is curved in general conformity with the curvature of the flight or thread of the screw 22. The sides 35 12a are generally vertical or parallel and the roof 12b is generally flat or horizontal. In carrying out the invention the roof is preferably reinforced or thickened as indicated at 12c and the under or inner face of this reinforced portion is curved or shaped as indicated at 12d in conformity with the perimeter of the conveyer screw and of the bottom of 40 the elbow. In other words, the curvature at 12d is substantially concentric with the screw 45 as it turns about its center of rotation 22a.

This construction provides instead of a restricted or limited point of bearing contact for the screw an extended bearing face which may afford something like five inches in 50 width of surface contact, when used with a screw of approximately 9" in diameter. The length of the thickened portion, as will be observed from Fig. 1, provides for engagement with one turn only of the screw, thus avoiding unnecessary friction which would result if the bearing were extended in length. 55

When at rest the forward end of the conveyer screw may contact with the bottom of 60 the conduit as shown in Fig. 1 but in operation, the screw will lift as has been explained and will bear against the curved face 12d as it rotates.

The improved construction does not otherwise alter the shape and design of the parts

so that recesses 23 are left within the conduit to minimize useless churning and promote the advance of the fuel therethrough under the rotating action of the screw conveyer.

A modification of the invention is illustrated in Figs. 4 and 5 which show a form of elbow 11b having a detachable roof portion 24 secured in place by bolts or screws 25. The roof portion 24 is thickened or reinforced as in the prior construction so as to provide an extended bearing surface 24a for the conveyer screw 22 as it lifts or rises during operation; otherwise the construction is substantially the same as that shown in Figs. 1 and 3. It possesses the advantage, however, of enabling the roof section to be discarded when worn out without necessitating replacement of the conduit as a whole; and it is to be understood that its use is not restricted to locomotive stokers or to mechanical stokers 85 of any specific construction.

It will be apparent that as the wear of the bearing surface 12d or 24a takes place that the surface contact increases, thereby further reducing the wearing or cutting 90 action of the screw and increases the life of the elbow casting.

Various other changes may be made without departing from the spirit and scope of the invention.

I claim:

1. A conduit elbow for a stoker having upright sides and a roof portion, the inner face of its roof portion being provided with a curved bearing surface terminating short of 100 said upright sides.

2. A conduit elbow for a stoker having upright sides and a flat roof portion, said flat roof being provided with an inner bearing surface curved concentrically with the screw 105 conveyer of the stoker terminating short of said upright sides.

3. An angular conduit elbow for a stoker, said element comprising a horizontally disposed portion and an upwardly curved or 110 elbow portion, the roof of the horizontal portion having a depending segment providing recesses or pockets between the sides of said depending segment and the inner wall of said horizontally disposed portion, the bottom surface of said depending segment being curved to provide a bearing surface for a 115 conveyer screw.

4. In a stoker, the combination of a conduit system comprising a horizontally disposed portion and an upwardly curved portion, a conveyer screw disposed within the horizontally disposed portion and terminating at the upwardly curved portion, the forward part of the horizontally disposed portion just short of the upwardly curved portion having upright sides and a roof formed with a curved bearing surface for the thread of the screw 125 as it lifts automatically during operation, 130

said curved bearing surface terminating short of said upright sides.

5. In a stoker, a conduit member adapted to receive a conveyer screw, said member considered in cross section having a curved bottom and a reinforced flat top or roof curved at its under side in conformity with the screw and providing a bearing surface for said screw, the sides of the member being upright 10 and providing fuel recesses or pockets at opposite sides of the curved bearing surface of the roof.

6. In a stoker, a conduit member adapted to receive a conveyer screw, said member having an arcuate shaped bottom, a substantially horizontal top or roof a portion of which at its under side is curved concentrically with said conveyer screw and providing a bearing surface for said screw, the 15 side walls of the member extending upwardly from its arcuate bottom to its top or roof, said side walls and roof providing at their intersection recesses or pockets at opposite sides of the curved bearing surface of the roof.

25. In testimony whereof I affix my signature.
F. C. PICKARD.
